(57) CLAIM

We claim the ornamental design for a gooseneck trailer mirror bracket, substantially as shown.

DESCRIPTION

FIG. 1 is a perspective view of the mirror bracket for use on a gooseneck trailer, in accordance with the present invention. FIG. 2 is a front elevation view of the mirror bracket shown in FIG. 1.

FIG. 3 is a rear elevation view of the mirror bracket shown in FIG. 1.

FIG. 4 is a top plan view of the bracket of FIG. 1.

FIG. 5 is a bottom plan view of the mirror bracket of FIG. 1. FIGS. 6 and 7 are elevation views from opposite sides of the mirror bracket of FIG. 1; and,

FIG. 8 is a perspective view of the mirror bracket of FIG. 1 mounted on the vertical hitch post of a gooseneck trailer, with a mirror on the bracket.

No claim is made to the truck, trailer or mirror shown in broken lines.
